UNITED STATES PATENT OFFICE

155,404

DESIGN FOR AN AIRPLANE

William K. Ebel, Baltimore County, Albert J. Subasky, Baltimore, and Willem D. van Zelm, Baltimore County, Md., assignors to The Glenn L. Martin Company, Baltimore, Md.

Application November 28, 1947, Serial No. 142,871

Term of patent 14 years

(Cl. D71—1)

To all whom it may concern:

Be it known that we, William K. Ebel, Albert J. Subasky, and Willem D. van Zelm, citizens of the United States and residents, respectively, of county of Baltimore, State of Maryland; city of Baltimore, State of Maryland; and county of Baltimore, State of Maryland; have invented a new, original, and ornamental Design for an Airplane, of which the following is a specification, reference being had to the accompanying drawings, forming a part thereof.

Figure 1 is a top plan view of an airplane embodying our new design.

Figure 2 is a side elevational view thereof showing by dotted lines the landing gear in the extended position and showing the jet engine air scoop on the nacelle in closed position.

Figure 3 is a front elevational view thereof showing by dotted lines the landing gear in the extended position and showing the air scoops on the nacelles in closed position.

Figure 4 is a bottom perspective view showing the airplane of our design, and particularly showing the novel nacelles for the tandem and reciprocating jet engines, with the air scoops for the jet engines in open position.

Figure 5 is a top perspective view of the airplane with the air scoops open.

Figure 6 is a fragmentary perspective view

from the rear of the wing, showing one of the tandem engine nacelles with its air scoop open.

The characteristic features of our design reside in the portions shown by means of full lines in the drawing.

We claim:

The ornamental design for an airplane, substantially as shown and described.

WILLIAM K. EBEL.

ALBERT J. SUBASKY.

WILLEM D. VAN ZELM.
